UNITED STATES PATENT OFFICE.

CHARLES A. SUHR, OF CHICAGO, ILLINOIS.

EARTH-AUGER.

1,106,425.

Specification of Letters Patent. Patented Aug. 11, 1914.

Application filed January 5, 1914. Serial No. 810,394.

To all whom it may concern:

Be it known that I, CHARLES A. SUHR, a citizen of the United States, and a resident of the city of Chicago, county of Cook, and 5 State of Illinois, have invented certain new and useful Improvements in Earth-Augers, of which the following is a specification.

My invention relates to improvements in earth augers and has for its object the 10 provision of an improved construction of this character the blades of which may be readily sharpened or reset and which is strong and durable in use.

The invention consists in the combinations 15 and arrangements of parts hereinafter described and claimed.

The invention will be best understood by reference to the accompanying drawing forming a part of this specification, and in 20 which—

Figure 1 is a partial side view, shown partially in section, of an earth auger embodying my invention, Fig. 2, a section taken on line $x-x$ of Fig. 1, and Fig. 3, a section 25 taken on line $y-y$ of Fig. 2.

The preferred form of construction as illustrated in the drawing comprises the usual auger blades 1 which are adapted to bore a hole, such as a post hole in the earth 30 when turned, as will be readily understood by those skilled in the art. At its upper end each of the blades 1 is provided with a bracket 2 which extends but little above the upper end of the blade and then turns 35 inwardly sharply at substantially right angles to said blades and overlaps the corresponding portion of the bracket on the other blade. Each of the brackets 2 is recessed at 3 to receive the corresponding 40 portion of the other bracket so that when said brackets are secured together, they form practically a continuous yoke or bridge connecting the blades. Each of the brackets is provided with one half of a 45 handle socket 4 provided at the bottom with a flange 5, said handle socket portions and flange being so shaped as to complete a socket having a closed bottom when said bracket members 2 are secured together by 50 means of bolts 6 as indicated. After the socket has been completed by securing the bracket members together by bolts 6, said socket is threaded and a handle 7 is threaded 55 to fit into said socket as shown. At its upper end the handle 7 is provided with a

cross bar 8 to facilitate the turning of the blades in the earth for forming a hole therein as will be readily understood. By this arrangement it will be observed that the blades 1 may be readily detached from each other 60 and the handle to facilitate sharpening or resetting of the same. By extending the brackets 2 upwardly from blades 1 but little and turning them inwardly and sharply at substantially right angles thereto, the connection with the handle 7 is made at the shortest possible distance from the blades thus subjecting the socket portions and the connecting bolt 6 to the minimum strain when the implement is in actual use. Inasmuch as the auger action of the blades introduces large strains into the implement which, of course, are increased immensely when a stone or other hard object is encountered, the strength of the handle connection and the character of the strain transmitted thereto is of much importance, and this arrangement of the brackets is well adapted to resist such strains. By providing a handle socket with a closed bottom the 70 75 80 strength of the arrangement is further increased.

While I have illustrated and described the preferred form of construction for carrying my invention into effect, this is capable of 85 variation and modification without departing from the spirit of the invention. I, therefore, do not wish to be limited to the precise details of construction set forth, but desire to avail myself of such variations 90 and modifications as come within the scope of the appended claims.

Having described my invention what I claim is new and desire to secure by Letters Patent is:

1. An earth auger comprising two blades; a supporting bracket at the upper end of each of said blades; each of said brackets being provided with a portion of a handle socket coöperating with the portion on the other to complete the socket when said brackets are secured together; means for detachably securing said brackets together; and a handle secured in said socket, substantially as described.

2. An earth auger comprising two blades; a supporting bracket at the upper end of each of said blades, each of said brackets being provided with a portion of a threaded handle socket coöperating with a portion on

the other to complete the socket when said brackets are secured together; means for detachably securing said brackets together; and a handle threaded in said socket, substantially as described.

3. An earth auger comprising two blades; a supporting bracket at the upper end of each of said blades, each of said brackets being provided with a portion of a handle 10 socket coöperating with the portion on the other to complete a socket having a closed bottom when said brackets are secured together; means for detachably securing said brackets together; and a handle secured in 15 said socket, substantially as described.

4. An earth auger comprising two blades; a supporting bracket at the upper end of each of said blades, each of said brackets being provided with a portion of a threaded 20 handle socket coöperating with the portion on the other to complete a socket having a closed bottom when said brackets are secured together; means for detachably securing said brackets together; and a handle

threaded in said socket, substantially as de- 25 scribed.

5. An earth auger comprising two auger blades; a supporting bracket at the upper end of each of said blades, said brackets extending but slightly above said blades and 30 then turning inwardly sharply at substantially right angles to the blades and overlapping each other, each of said brackets being provided with a portion of a threaded handle socket coöperating with the portion 35 on the other to complete a socket having a closed bottom when said brackets are secured together; means for detachably securing said brackets together; and a handle threaded in said socket, substantially as de- 40 scribed.

In testimony whereof I have signed my name to this specification in the presence of two subscribing witnesses.

CHARLES A. SUHR.
